PRIMING ARRANGEMENT FOR GASOLINE
AND LIKE ENGINES

Joseph Anthony Hunt, Redditch, England, assignor to The Heywood Compressor Company Limited, Redditch, England, a British company

Application February 15, 1945, Serial No. 578,099
In Great Britain September 1, 1944

6 Claims. (Cl. 123—180)

1

This invention has for its object to provide improved means for effecting the priming of gasoline and like engines.

The invention consists in a priming arrangement for gasoline and like engines comprising, in combination, a fuel tank, a float controlled fuel inlet to such tank, an electro-magnetically controlled valve for controlling the delivery from said tank, a sprayer receiving fuel from said tank past said valve, a compressed air supply pipe to said tank, an electro-magnetically controlled valve for controlling the supply of compressed air to and the venting of said tank, a switch for closing an electric circuit including a hold-on coil for the switch and the windings of the said electro-magnetically controlled valves, a normally closed make and break device in said circuit, bellows operated means for opening said device to break the circuit, and a capsule warmed by the engine to cause the bellows to open the make and break device when the engine temperature reaches a predetermined minimum.

The invention further consists in a priming arrangement for gasoline and like engines comprising, in combination, a fuel tank, a float controlled fuel inlet to such tank, an electro-magnetically controlled valve for controlling the delivery from said tank, a sprayer receiving fuel from said tank past said valve, a compressed air supply pipe to said tank, an electro-magnetically controlled valve for controlling the supply of compressed air to and the venting of said tank, a switch for closing an electric circuit including a hold-on coil for the switch and the windings of the said electro-magnetically controlled valves, a normally closed make and break device in said circuit, bellows operated means for opening said device to break the circuit, and a capsule heated by a coil in the circuit to cause the bellows to open the make and break device when the circuit has been closed for the time requisite to warm the capsule to a predetermined extent.

The invention further consists in the arrangement of two capsules, one warmed by the engine being primed and the other warmed by current in the electric circuit for opening the make and break device.

The accompanying explanatory diagram gives a lay-out of a priming arrangement in accordance with this invention.

a is the priming fuel tank into which fuel flows by gravity or under a slight pressure through the branch *b* which has a non-return valve *c* therein. There is a valve *d* controlled

2

by the float *e* to control the flow of fuel into the tank. The outflow from the latter to the priming sprayers *f* is controlled by the valve *g* which constitutes a solenoid core and is raised to allow fuel to flow from the tank *a* to the sprayers *f* when electric current is passed through the winding *h*. The valve is closed by the spring *i* when the winding *h* is de-energised.

The expulsion of fuel from the tank *a* is effected by air pressure applied through the pipe *j* and controlled by the valve *k* which constitutes a solenoid core and is raised to allow compressed air to pass to the tank when the winding *m* is energised. When the valve *k* is raised and open, the other end *n* of the core acts as a venting valve and closes the connection to atmosphere at *o*, the latter serving when the valve *k* is closed to allow the tank *a* to exhaust to atmosphere as it is filling. A spring *p* serves to close the valve *k* when the winding *m* is de-energised.

The electric circuit which includes the windings *h* and *m*, also includes a hold-on coil *q* for the push button switch *r*, the latter when depressed closing the contacts *s* and *t* in the circuit which includes the hold-on coil *q*, the windings *h* and *m* and a make-and-break device *u*. Normally the make-and-break device is closed and a plunger *v* which serves to open such device and break the electric circuit is retained clear thereof by the bellows *w*. The space *x* around the bellows *w* and the capsules *y* and *z* in communication with the space *x* contain a suitable high expansion fluid.

The capsule *z* is placed against a suitable part 35 *2* of the engine being primed so that it is influenced by engine temperature and the capsule *y* is wound with a heating coil *3* in the electric circuit so that it is heated proportionately to the time that the circuit has been closed. When 40 therefore the engine temperature exceeds a predetermined minimum or the circuit has been closed for such a time that the coil *3* becomes sufficiently heated, the capsule *w* will be compressed by the high expansion fluid and will by the plunger *v* open the make-and-break device *u*, so breaking the electric circuit and de-energising the coils *h*, *m* and *q*. The valves *p* and *e* will then be closed, and the push button switch opened by the spring *r*.

As shown, the push button switch is open, the windings *h* and *m* de-energised and the make-and-break device *u* closed. Fuel can now flow into the tank *a* if the level therein is below a predetermined amount.

To cause priming of the engine, the push but-

ton r is depressed and closes the contacts s, t so completing the circuit which includes the hold-on coil q , the windings m and h and the make-and-break device u .

The atmospheric vent valve n is now closed and compressed air enters the float chamber a and delivers priming fuel via the valve e which is open to the sprayers f . If the engine starts, it will warm the capsule z and the time that the electric circuit is closed will cause a warming of the capsule y , which will eventually result in the bellows w being compressed and causing the plunger v to open the make-and-break device u , so de-energising the windings q, h and m and restoring the system to its original condition, when the tank a can re-fill. If the engine does not start, the heating of the capsule y will act as a safety means to prevent excessive priming.

The air and fuel valves when closed prevent any dribbling at the priming atomiser, and ensure a prompt priming of the engine for any predetermined interval of time, or until the engine warms up.

What I claim is:

1. A priming arrangement for gasoline and like engines comprising, in combination, a fuel tank, a float controlled fuel inlet to such tank, an electro-magnetically controlled valve for controlling the delivery from said tank, a sprayer receiving fuel from said tank past said valve, a compressed air supply pipe to said tank, an electro-magnetically controlled valve for controlling the supply of compressed air to and the venting of said tank, a switch for closing an electric circuit including a hold-on coil for the switch and the windings of the said electro-magnetically controlled valves, a normally closed make and break device in said circuit, bellows operated means for opening said device to break the circuit, and a capsule warmed by the engine to cause the bellows to open the make and break device when the engine temperature reaches a predetermined minimum.

2. In a priming arrangement for gasoline and

the like engines comprising, in combination, a fuel tank, a float controlled fuel inlet to such tank, an electro-magnetically controlled valve for controlling the delivery from said tank, a sprayer receiving fuel from said tank past said valve, a compressed air supply pipe to said tank, an electro-magnetically controlled valve for controlling the supply of compressed air to and the venting of said tank, a switch for closing an electric circuit including a hold-on coil for the switch and the windings of the said electro-magnetically controlled valves, a normally closed make-and-break device in said circuit, bellows operated means for opening said device to break the circuit, and a capsule heated by a coil in the circuit to cause the bellows to open the make and break device when the circuit has been closed for the time requisite to warm the capsule to a predetermined extent.

3. In a priming arrangement as claimed in claim 1, a capsule heated by a coil in the circuit, also adapted to cause the bellows to open the make and break device when the circuit has been closed for a predetermined period.

4. In a priming arrangement as claimed in claim 1, the construction of the valve for controlling the flow of compressed air to the fuel tank in which the valve is a solenoid core, one end of which controls the flow of compressed air to the tank and the other end of which vents the tank when the compressed air is cut off.

5. In a priming arrangement as claimed in claim 1, the construction of the valve for controlling the delivery from the fuel tank as a solenoid core.

6. In a priming arrangement as claimed in claim 1, a chamber around the bellows communicating with the capsule, said chamber and capsule containing a highly expansible liquid, a plunger connected to said bellows adapted when the bellows is compressed to engage and open the make and break device.

JOSEPH ANTHONY HUNT.
